UNITED STATES PATENT OFFICE.

EDWIN CALDWELL, OF NEW YORK, N. Y.

SMOKER'S ARTICLE.

Application filed March 11, 1924. Serial No. 698,379.

This invention relates to smokers' articles such as ash trays and receptacles, and especially to the support of cigars and cigarettes therefrom. An object of the invention is to provide an improved article of this type for receiving ashes and cigar and cigarette stubs, and for supporting cigars and cigarettes in a safe and sanitary manner and extinguishing the same, which may be used satisfactorily in vehicles and other places where there are air currents. A further object is to provide an improved ash receptacle and cigarette and cigar support of this type which may be attached to any suitable part of a motor vehicle so as to be convenient for use in receiving ashes, and in supporting and extinguishing cigars and cigarettes; which may be readily removed so that it can be hanged for use to different parts of the vehicle; which can be readily cleaned and emptied; and which has provision for supporting a package of matches.

A further object is to provide an improved cover for ash receptacles, which may be made of sizes and shapes to fit any desired receptacle, and which will support cigars and cigarettes in a sanitary and safe manner, and which will extinguish them before they have burned sufficiently to release themselves. Other objects and advantages will be apparent from the following description of an embodiment of the invention, and the novel features will be particularly pointed out hereinafter in claims.

35 In the accompanying drawing:

Fig. 1 is a perspective of an ash receptacle and cigar and cigarette support embodying the invention and which may be attached to the framework of an automobile body;

40 Fig. 2 is a transverse sectional elevation of the same;

Fig. 3 is another transverse sectional elevation of the same taken substantially along the line 3—3 of Fig. 2;

45 Fig. 4 is a sectional plan of the same taken substantially along the line 4—4 of Fig. 3;

Fig. 5 is a perspective of the cover;

Fig. 6 is a plan of a receptacle constructed in accordance with the invention and illustrating another embodiment thereof; and

50 Fig. 7 is a longitudinal sectional elevation of the same.

Referring particularly to Figs. 1 to 5, a channel member 1 having side arms 2 is provided in its bottom or main wall with apertures 3 through which suitable securing

means, such as screws 4, may be passed into a supporting wall 5 (see Fig. 2) such as the wall of an automobile or other vehicle. The side arms 2 of the channel member along 60 their free side edges, are turned or bent toward one another, to form flanges 6, and at their lower ends are turned toward one another to form flanges or abutment means 7 which are separated by a finger space 8 for 65 a purpose to be presently explained.

A receptacle 9, preferably formed of sheet metal, is provided of a size and shape to slide into the channel member endwise of the latter, being confined against lateral removal 70 therefrom by the flanges 6. One or more of the side edges of the container 9 are extended upwardly and rolled outwardly upon themselves to form beads 10 which engage with the upper ends of the side arms 2 of the 75 channel member and limit downward movement of the container 9 within the channel member.

When the container is within the channel member, the bottom wall 11 of the container 80 is spaced above the inturned flanges 7 at the bottom of the channel member so as to provide in the bottom of the channel member a space in which a package or box of matches 85 A may be stored and exposed through the channel member between the flanges 6, so as to be removable through the space between the flanges 6. The removal of the package or box of matches may be accomplished by inserting one's finger upwardly 90 through the slot or space 8 between the flanges 7, so as to engage with the package or box of matches and pull it forwardly from the channel member.

The container is provided with a removable cover 12 having front and rear flanges 13 which depend over and frictionally grip opposite lateral walls of the container for preventing accidental or unintentional removal of the cover from the container. The 100 cover is provided with an aperture 14 through which ashes or cigar and cigarette stubs may be inserted into the container, and the cover will prevent the blowing out of the ashes from the container when the latter is 105 placed in a position where it is subject to air draughts. The cover is also provided with slots or notches 15 opening into the aperture 14 so as to provide opposing walls between which a cigar or cigarette may be 110 wedged, and supported therefrom, with an end of the cigar or cigarette depending into

the interior of the container and the other end projecting above the cover.

A downwardly tapered tubular sleeve 16 passes through and depends from the cover 12 into the container, and has a downwardly tapering or convergent inner bore or passage which will wedgingly receive an end of a cigar or cigarette and support it above the container. The sleeve 16 and the cover 12 are preferably made of metal so that when a cigar or cigarette is wedged in either, the cigar or cigarette will be extinguished before it can burn sufficiently to release itself. In the case of the sleeve 16, the cigar or cigarette is preferably inserted therein lighted end first, and if made of metal or other heat-conducting material, the sleeve will conduct the heat from the burning tobacco at the lighted end and chill it below the temperature of combustion, thus extinguishing it within a short interval of time. When a cigar or cigarette is wedged in one of the notches 15, it will burn until it approaches in close proximity to the cover 20 and then before reaching the notch walls the burning tobacco will be chilled and extinguished.

In the use of this particular device, the channel member may be secured to a suitable wall or supporting object so as to be substantially upright, and the container 9 is slid downwardly into the same, as shown in Fig. 1. A package of matches may be inserted into the chamber at the lower end 35 of the channel member. The ashes from the cigars or cigarettes may be inserted through the aperture 14 into the container, and a cigar or cigarette may be supported in either the sleeve 16 or the notches 15.

It will be observed that by the use of the cover in this manner as the support for the cigars and cigarettes with lighted ends down, air currents cannot blow ashes or burning tobacco from the cigars or cigarettes into the vehicle or upon occupants thereof, the lighted ends being protected from the air currents, so that in case any ashes or burning tobacco become loose or separate from the cigars or cigarettes, they will fall directly into the container and do no harm. At the same time the air currents cannot reach the ashes deposited in the container and blow them around to the annoyance of the occupants of the vehicle.

The container may be quickly removed from the channel member by sliding it upwardly therefrom, so that it may be passed to different occupants of the vehicle if this is desired, and may be replaced in the channel member when not in use. To clean the container it is merely necessary to remove the cover, which is frictionally clamped or secured thereon by the flanges 13, and dump or brush out the contents.

In Figs. 6 and 7, a suitable base 17 is pro-

vided with an annular flange 18 upon its upper face, over which a tubular shell 19 may be placed with sufficient friction to couple them. The shell 19 is substantially closed at its upper end by a cover 20 which is similar to the cover 12 of Figs. 1 to 4, the cover 20, however, having a flange 21 depending into the interior of the shell 19, instead of over the exterior thereof. The depending flange by frictional engagement 75 with the shell anchors the cover in place and at the same time permits of its removal when necessary or desirable. The cover extends slightly outwardly from the depending flange so as to rest upon the upper end edge 80 of the shell 19.

This cover is provided with an aperture 22 through which ashes or cigar and cigarette stubs may be inserted into the container formed by the base 17 and the shell 19, and also is provided with slots or notches 23 in the wall of the aperture 22 of such a width that a cigar or cigarette may be wedged therein for support, these notches 23 corresponding to the notches 15 of the embodiment of the invention shown in Figs. 1 to 4. One or more sleeves 24 may pass through and depend from the cover into the interior of the shell for supporting and extinguishing cigars or cigarettes, these sleeves corresponding with the sleeve 16 of Figs. 1 to 4.

The sleeves 24 are smaller at their lower ends and the bore converges downwardly so as to provide a tapering conduit into which a cigar or cigarette may be inserted, lighted end first, and wedged therein. The extinguishing action of the notches 23 and the sleeves 24 is the same as that explained in connection with the notches 15 and the sleeve 16 in Figs. 1 to 4. An imperforate cap 25 may be applied to the upper end of the shell 19 over the cover 20 so as to close the aperture 22 completely.

With this type of container the cap 25 may be removed to permit of the insertion of ashes or stubs through the aperture 22, and the container may be passed around or carried about as desired for convenient use. By placing the cap 25 thereon, the container may be carried about in any position without danger of the ashes or the stubs falling out. The container may be readily cleaned by separating the shell 19 from both its cover and the base 17.

It will be understood that the illustrated shapes, sizes and types of containers upon which the cover may be placed, are merely examples for the purpose of explaining the nature of the invention, and that these types of covers may be applied to the ordinary ash trays of smoking stands, or to any other style or design of receptacle. The parts may all be made of metal, or partly of metal and partly of other materials, or entirely of non-metallic material. At least the cover and

snuffer sleeves are preferably made of metal so as to extinguish the cigars or cigarettes in the manner explained.

It will be obvious that various other changes in the details and arrangements of parts, herein described and illustrated for the purpose of explaining the nature of the invention, may be made by those skilled in the art within the principle and scope of the invention as expressed in the appended claims.

I claim:

1. A cigar and cigarette support comprising an ash receptacle with an aperture in a wall through which ashes may be inserted into the receptacle and opposing walls in the aperture of a width slightly less than the diameter of a cigar or cigarette between which opposing walls a cigar or cigarette 20 when wedged may be supported so as to extend into the receptacle.

2. An ash receptacle comprising a container having an open face for the reception of ashes with a wall extending partially 25 across said open face, said wall having in the edge across the open face an approximately U-shaped notch therein of a width slightly less than the diameter of a cigarette and of a depth at least sufficient to receive a cigarette, whereby a cigarette may be wedged in said notch and without injury supported entirely thereby partially into the said open face.

3. An ash receptacle comprising a container having an open face for the reception of ashes with a metal wall extending partially across said open face, said wall having in the edge across the open face an approximately U-shaped notch therein of a width 40 slightly less than the diameter of a cigarette and of a depth at least sufficient to receive a cigarette, whereby a cigarette may be wedged in said notch and without injury supported entirely thereby partially into the said open face, and be extinguished automatically, without releasing itself from the notch, by conduction of the metal wall if the cigarette burns into proximity to the wedged section.

50 4. An ash receptacle comprising a frame for attachment to a support and having guides, and a receptacle slideable into and out of said guides of the frame to permit of attachment thereto or detachment therefrom of said receptacle, said receptacle having an open face for the reception of ashes and with a wall extending partially across said face and formed to support a cigarette thereover.

55 5. A cover for ash receptacles having opposing walls between which a cigar or cigarette may be wedged, the opposing walls being of metal whereby the cigar or cigarette will be extinguished, if burning, before it burns sufficiently near the walls to release it self.

6. A cover for ash receptacles having an interior aperture with a notch leading from the aperture in which a cigar or cigarette may be wedged for support therefrom with an end depending below the upper face of the 70 cover.

7. A cover for ash receptacles having an interior aperture with opposing walls in the aperture between which a cigar or cigarette may be wedged for support therefrom with 75 an end depending below the upper face of the cover.

8. An ash receptacle comprising a channel member for permanent attachment in a substantially vertical position to a supporting 80 object, and having its side arms flanged toward one another, a container slideable into the channel of the member end-wise thereof to be supported therefrom, said container having in a wall an aperture for the insertion of tobacco stubs.

9. An ash receptacle comprising a channel member for permanent attachment in a substantially vertical position to a supporting 90 object, and having its side arms flanged toward one another, a container slideable into the channel of the member end-wise thereof to be supported therefrom, said container having in a wall an aperture for the insertion of tobacco stubs, with opposing walls 95 within the limits of the aperture, between which opposing walls a cigar or cigarette may be wedged for support so as to extend through the aperture.

10. An ash receptacle comprising a channel member for permanent attachment in a substantially vertical position to a supporting object, and having its side arms flanged toward one another, a container slideable into the channel of the member end-wise 100 thereof to be supported therefrom, said container having in a wall an aperture for the insertion of tobacco stubs, the container and channel member having coacting abutments 105 which limit the movement of the container into the channel member.

11. An ash receptacle comprising a channel member for permanent attachment in a substantially vertical position to a supporting object, and having its side arms flanged 115 toward one another, a container slideable into the channel of the member end-wise thereof to be supported therefrom, said container having in a wall an aperture for the insertion of tobacco stubs, the container and channel member having coacting abutments 120 which limit the movement of the container into the channel member, the channel member having end abutment means serving with the inner end of the container as a chamber 125 for the support of a package of matches.

12. An ash receptacle comprising a channel member for permanent attachment in a substantially vertical position to a supporting object, and having its side arms flanged

- 4
- toward one another, a container slidable into the channel of the member end-wise thereof to be supported therefrom, said container having in a wall an aperture for the insertion of tobacco stubs, the container and channel member having coacting abutments which limit the movement of the container into the channel member, the channel member having inturned flanges at the inner end serving 5 with the inner end of the container as a chamber for the support of a package of matches, the space between the last named flanges providing a finger space to facilitate the removal of the package of matches.
13. An ash receptacle comprising a channel member for permanent attachment in a substantially vertical position to a supporting object, and having its side arms flanged toward one another, a container slidable into the channel of the member end-wise thereof to be supported therefrom, said container having in a wall an aperture for the insertion of tobacco stubs, the side walls of the container being rolled upon themselves at the end last to enter the channel member to form beads which, by engagement with the end of the channel member, limit movement of the container into the channel member.
14. An ash receptacle comprising a channel member for permanent attachment in a substantially vertical position to a supporting object, a container slidable into the channel of the member end-wise thereof to be supported therefrom, said container having in a wall an aperture for the insertion of tobacco stubs, with opposing walls within the limits of the aperture, between which opposing walls a cigar or cigarette may be

wedged for support so as to extend through the aperture. 40

15. An ash receptacle comprising a channel member for permanent attachment in a substantially vertical position to a supporting object, a container slidable into the channel of the member end-wise thereof to be 45 supported therefrom, said container having in a wall an aperture for the insertion of tobacco stubs, the container and channel member having coacting abutments which limit the movement of the container into the 50 channel member, the channel member having inturned flanges at the inner end serving with the inner end of the container as a chamber for the support of a package of matches, the space between the last named 55 flanges providing a finger space to facilitate the removal of the package of matches.

16. An ash receptacle comprising a channel member for permanent attachment in a substantially vertical position to a supporting object, a container slidable into the channel of the member end-wise thereof to be supported therefrom, said container having in a wall an aperture for the insertion of tobacco stubs, the container and channel 60 member having coacting abutments which limit the movement of the container into the channel member, the side walls of the container being rolled upon themselves at the end last to enter the channel member to form 65 beads which, by engagement with the end of the channel member, limit movement of the container into the channel member. 70

In witness whereof, I hereunto subscribe my signature.

EDWIN CALDWELL.
